UNITED STATES PATENT OFFICE.

RUDOLF HUNDAUSEN, OF WILMERSDORF, GERMANY, ASSIGNOR TO THE SIEMENS & HALSKE ELECTRIC COMPANY OF AMERICA, OF CHICAGO, ILLINOIS.

SYSTEM OF NON-INTERCHANGEABLE CONTACT PARTS.

SPECIFICATION forming part of Letters Patent No. 664,046, dated December 18, 1900.

Application filed November 4, 1899. Serial No. 735,762. (No model.)

To all whom it may concern:

Be it known that I, RUDOLF HUNDAUSEN, a subject of the Emperor of Germany, residing at Wilmersdorf, near Berlin, Germany, 5 have invented a certain new and useful Improvement in Systems of Non-Interchangeable Contact Parts, (Case No. 251,) of which the following is a full, clear, concise, and exact description, reference being had to the 10 accompanying drawings, forming a part of this specification.

My invention relates to a system of non-interchangeable contact parts, and has for its object the provision of improved means for 15 preventing the improper establishment of connection between the terminals of an electric circuit.

More particularly, my said invention aims to prevent the insertion in a given terminal 20 socket of a fuse, lamp, or other translating device or plug for supplying circuit to other translating devices the capacity of which is greater than that designed for the socket.

In many instances it is highly desirable to 25 secure electrical apparatus wherein the translating devices or other conducting parts of various capacities are not interchangeable. The necessity for such apparatus is at once apparent when it is considered that in electrical practice certain portions of the apparatus are used and controlled by those who 30 are unskilled in the art or are desirous of using translating devices of greater capacity than those for which the proposed circuit con- 35 sidered is designed. It has heretofore been proposed to provide devices for accomplishing these results; and my invention herein consists in a specific improvement of mechanism designed for the purpose named.

40 In accordance with my present invention I provide upon the plugs and sockets of the system slots and lugs, the plugs and sockets to be used in supplying translating devices of larger capacity having the engaging recesses and lugs or pins of larger size, and the 45 plugs and sockets to supply translating devices of smaller capacity having the engaging slots and pins thereof of smaller size, whereby it would be impossible to insert the 50 plug of the translating device of larger ca-

pacity into the socket designed to be associated with a translating device of smaller capacity. It is to be understood that each slot is provided upon one of the engaging parts, as the socket, and that the corresponding lug 55 is provided upon the other engaging part, as the plug.

My invention will be more readily understood by reference to the accompanying drawings, which illustrate the preferred embodiment thereof and show the use of the invention as applied to incandescent electric lighting.

In the drawings, Figure 1 shows an incandescent lamp and its associated socket, the 65 lamp and socket being separated. Fig. 2 shows a lamp of larger capacity or greater candle-power and its associated socket, the two being separated. Fig. 3 shows the lamp and its socket illustrated in Fig. 1 assembled. 70 Fig. 4 shows the lamp and socket illustrated in Fig. 2 assembled.

Like parts are indicated by similar letters of reference throughout the different figures.

While I have shown incandescent lamps as 75 being the precise devices through which current is supplied and by which the current is utilized, it is obvious that other translating devices and conducting means may be employed.

80 The plug *a* of the conducting means or translating device shown in Figs. 1 and 3 is mechanically fixed with relation to the translating device; but it is to be understood that this relative mechanical disposition of the 85 translating device and plugs is not essential. The lamp or translating device *b*, having the smaller capacity, is provided with a projecting lug *c* of small size, and the socket *d*, into which the plug is to be inserted, is provided 90 with a slot of a corresponding size, into which the lug or pin *c* must be inserted in order that the plug *a* shall enter the socket. Each of the sockets shown contains any suitable form of terminals *ff*, adapted for contact with terminals *gg*, carried upon the plugs. The terminals *ff* are preferably movable longitudinally in hollow guides *mm*, a spring or springs *n* serving to exert an upward force thereon, thereby securely holding the pins *c* in their 95 100

respective slots. The translating device *h* being of larger capacity, I provide the plug *i* thereof with a lug *k*, which is larger than the lug *c*, and also provide the sockets into which 5 the said plugs may be inserted with slots *l* of a size corresponding to the lugs *k*, the lugs having to be inserted within the said slots in order to permit of the insertion of the plugs in the sockets to complete the connection of 10 the translating device with the supply-conductor.

It will be observed that the lugs *c* and *k* project transversely or laterally from the plugs and that the slots *e* and *l* are disposed 15 at the mouths of the sockets and extend longitudinally thereof.

While I have shown the sockets as being provided with the slots and the plugs as being provided with the pins or lugs, it is obvious 20 that this arrangement might be varied without departing from the spirit of the invention.

The slots *e* and *l* in the sockets are preferably provided with lateral extensions to form 25 bayonet-catches, as shown, whereby the pins after being inserted within the slots may also serve to secure the engagement between the plugs and the sockets.

Having thus described my invention, I 30 claim as new and desire to secure by Letters Patent—

1. In a system of non-interchangeable electrical contact appliances, the combination with a plurality of engaging elements in the 35 form of sockets, of a second plurality of engaging elements in the form of plugs, laterally-projecting pins of different sizes provided upon one set of the engaging elements, and slots or recesses of different sizes provided 40 upon the other engaging elements, whereby circuit connections may be established and the improper insertion of connecting-plugs prevented, substantially as described.

2. In a system of non-interchangeable electrical contact appliances, the combination with a plurality of engaging elements in the 45 form of sockets, of a second plurality of engaging elements in the form of plugs, laterally-projecting pins of different sizes provided upon one set of the engaging elements, and longitudinally-disposed slots or recesses of 50 different sizes provided upon the other engaging elements, whereby circuit connections may be established and the improper insertion of connecting-plugs prevented, substantially as described.

3. In a system of non-interchangeable contact appliances, the combination with a plurality of contact-plugs provided with laterally-extending pins or lugs of different sizes, 60 of a plurality of sockets provided with slots or recesses of different sizes, whereby circuit connections may be established and improper insertions of the plugs within the sockets prevented, substantially as described.

4. In a system of non-interchangeable contact appliances, the combination with a plurality of contact-plugs provided with laterally-extending pins or lugs of different sizes, 70 of a plurality of sockets provided with slots or recesses of different sizes, the slots extending longitudinally of the sockets, whereby circuit connections may be established and improper insertions of the plugs within the sockets prevented, substantially as described. 75

5. In a system of non-interchangeable contact appliances, the combination with a plurality of contact-plugs provided with laterally-extending pins or lugs of different sizes, 80 of a plurality of sockets provided with bayonet slots or recesses of different sizes, the said bayonet-slots serving to prevent improper insertions of the plugs and coacting with the pins to secure the engagement between the plugs and sockets, substantially as described. 85

6. In a system of non-interchangeable contact appliances, the combination with a plurality of contact-plugs provided with laterally-extending pins or lugs of different sizes, 90 of a plurality of sockets provided with bayonet slots or recesses of different sizes, the slots extending longitudinally of the sockets, the said bayonet-slots serving to prevent improper insertions of the plugs and coacting with the pins to secure the engagement between the plugs and sockets, substantially as described. 95

7. In a system of non-interchangeable contact appliances, the combination with a plurality of contact-plugs provided with pins or 100 lugs of different sizes, of a plurality of sockets provided with bayonet slots or recesses of different sizes, the said bayonet-slots serving to prevent improper insertions of the plugs and coacting with the pins to secure the engagement between the plugs and sockets, substantially as described. 105

8. In a system of non-interchangeable electrical contact appliances, the combination with a plurality of engaging elements in the 110 form of sockets, of a second plurality of engaging elements in the form of plugs, laterally-projecting pins of different sizes provided upon one set of the engaging elements, 115 longitudinally-disposed slots or recesses of different sizes provided upon the other engaging elements, whereby circuit connections may be established and the improper insertion of connecting-plugs prevented, the terminals upon the plugs being adapted for engagement with terminals *f*, *f*, in the sockets, and springs *n* in engagement with the terminals *f*, *f*, substantially as described. 120

In witness whereof I hereunto subscribe my name this 10th day of October, A. D. 1899. 125

RUDOLF HUNDHAUSEN.
